UNITED STATES PATENT OFFICE.

JOHN WM. FLETCHER, OF TOCOPILLA, CHILE.

PIPE-CUTTING TOOL.

SPECIFICATION forming part of Letters Patent No. 628,403, dated July 4, 1899.

Application filed January 16, 1899. Serial No. 702,358. (No model.)

To all whom it may concern:

Be it known that I, JOHN WM. FLETCHER, of Tocopilla, Republic of Chile, South America, have invented a new and Improved Pipe-Cutting Tool, of which the following is a full, clear, and exact description.

My invention relates to an improvement in tools designed for cutting pipe, and is intended particularly for use in removing pipe from boilers.

My invention comprises the novel features of construction hereinafter described and claimed.

Reference is to be had to the accompanying drawings, forming a part of this specification, in which similar characters of reference indicate corresponding parts in all the figures.

Figure 1 is a broken side view of the cutting tool. Fig. 2 is an end view of the same seen in direction of arrow *x* in Fig. 1. Fig. 3 is a plan view of the device at right angles with the plane of Fig. 1. Fig. 4 is a longitudinal sectional view on the line 4 4 in Fig. 3, and Fig. 5 is a cross-section taken through the hinge between the two parts, substantially on the line 5 5 in Fig. 4.

Removing pipes or flues from boilers of a locomotive pattern is facilitated by cutting a short piece off of the end of the flue. This is usually done by some tool inserted in the end of the flue. My device is a tool adapted for this use and one which may be operated by ordinary hand-tools. The tool as a whole is shaped as a round bar having a flange adapted to rest against the end of the flue. The tool is composed of two parts, the main body *A* consisting of a bar which is of round or other suitable shape and is provided at its outer end with a squared portion *J*, adapted to receive a wrench. The portion of this tool which enters the flue is cut down to a half-cylinder or to approximately this size. At the point where the reduction in size is made it is also shaped so as to form a hinged joint upon which the hinged arm *B* is pivoted. As herein shown, the hinged arm *B* is provided with two jaws *B'*, embracing the central portion *A'* of the body-piece. The two are hinged together by a bolt *I*, passing through the parts.

The two arms of the device are provided with circumferential flanges *C* and *C'*, which

are opposite each other and are adapted to engage the end of the flue, and thus to hold the tool steady and in a fixed position. A set-screw *H* passes through the hinged member *B* and engages the flat surface of the half *A'* of the body-piece. By means of this set-screw the two arms may be separated as desired. That portion of the arm *A'* which is within the flue has a longitudinal slot *D*, within which is a block *E*, closely fitting said slot, but capable of sliding therein. A bolt *F* has threaded engagement through a perforation of the block *E* and is given a bearing at each end in the arm *A'*. At one of these bearings the bolt is provided with a peripheral groove, which receives a pin *G*, which holds the bolt in place and prevents longitudinal movement thereof. By turning the bolt the block *E* will thus be moved to either end of the slot. It may be adjusted, therefore, at any required distance from the shoulder *C* within the limits of the length of the slot. The block *E* has a cutting-point *e* projecting beyond the tool.

In using this device the block *E* is adjusted so that the cutting-point *e* is at a distance from the flange corresponding with the distance from the end of the pipe where it is desired to cut the pipe. The set-screw *H* is backed out until the two arms *A'* and *B* are in contact. The tool is then inserted within the pipe and the set-screw *H* turned inward until the point of the cutting-tool is in contact with the pipe. The tool is then turned by engaging the squared end *J* with a wrench or by any other suitable means. In the process of cutting the pipe the set-screw *H* is gradually adjusted inward, thus forcing the cutting-tool deeper into the pipe until the pipe has been cut off.

This device is comparatively small and inexpensive and not liable to get out of order. It may also be operated without requiring anything but ordinary hand-tools. By its use flues may be quickly removed from a boiler.

Having thus fully described my invention, I claim as new and desire to secure by Letters Patent—

1. A pipe-cutter, comprising a bar having two separable arms adapted to be inserted in a pipe alongside of each other, means for separating said arms and a cutter secured in one arm and adapted to engage the inner surface

- of the pipe, and means for longitudinally adjusting the cutter on its arm substantially as described.
2. A pipe-cutter, comprising two hinged arms adapted to lie alongside of each other and to enter the pipe, means for separating the two parts, and a cutting-tool secured to one part and adjustable longitudinally thereon, substantially as described.
- 10 3. A pipe-cutter, comprising two hinged arms adapted to lie alongside of each other, and to enter the pipe, means for separating the two parts, one of said parts having a longitudinal slot, and a block fitted to slide in said slot and having a projecting cutting end, substantially as described.
4. A pipe-cutter, comprising two hinged arms adapted to lie alongside of each other and to enter the pipe, one of said parts having a longitudinal slot, a block fitted to slide in said slot and having a projecting cutting end and a threaded hole, a bolt having a thrust-bearing in the bar and entering the hole in said block, and means for separating the two arms, substantially as described.
- 25 5. A pipe-cutter, comprising a bar having two separable arms adapted to be inserted in a pipe alongside of each other, a set-screw in one arm engaging the other by which they
- may be separated, a cutter secured in one arm and adapted to engage the inner surface of the pipe, and means for adjusting said cutter longitudinally of the device, substantially as described.
6. A pipe-cutter, comprising a bar having two separable arms adapted to be inserted in a pipe alongside of each other, and each having a collar adapted to engage the end of the pipe, means for separating said arms, a cutter secured in one arm and adapted to engage the inner surface of the pipe, and means for adjusting the cutter longitudinally of its arm, substantially as described.
7. A pipe-cutter, comprising two hinged arms adapted to lie alongside of each other and to enter the pipe, and each having a collar adapted to engage the end of the pipe, a set-screw passing through one arm and engaging the other by which the two may be separated, a cutting-tool mounted upon one arm and adapted to engage the inner surface of the pipe, and means for adjusting the position of said cutter longitudinally of the device, substantially as described.
